[57] CLAIM

The ornamental design for an anti-spill fluid receptacle, as shown and described.

DESCRIPTION

FIG. 1 is a front elevational view of the anti-spill fluid receptacle showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line lettering and drops of fluid in FIGS. 1, 2, and 3 is for illustrative purposes only and forms no part of the claimed design.

The broken portion in FIGS. 1 through 4 indicates indeterminate length of the orthogonal nose portion of the design.
